(57) CLAIM

The ornamental design for a bottle, as shown and described.

DESCRIPTION

FIG. 1 is a perspective view of a bottle according to our new and ornamental design;

FIG. 2 is a front elevation view thereof;

FIG. 3 is a rear elevation view thereof, wherein the left and right elevation views thereof are identical;

FIG. 4 is a top plan view thereof; and,

FIG. 5 is a bottom plan view thereof.

The dash-dot broken lines show the boundaries of the claimed design and form no part of the claim. The evenly dashed broken lines show portions of the bottle that form no part of the claim.

1 Claim, 4 Drawing Sheets
